UNITED STATES PATENT OFFICE

THOMAS H. SYMINGTON, DECEASED, LATE OF BALTIMORE, MARYLAND, BY EDITH R. SYMINGTON AND THOMAS R. SYMINGTON, EXECUTORS, OF BALTIMORE, MARYLAND, ASSIGNORS TO T. H. SYMINGTON & SON, INC., OF BALTIMORE, MARYLAND, A CORPORATION OF MARYLAND

TRUCK SIDE FRAME

Application filed November 11, 1931. Serial No. 574,435.

The invention relates to side frames for railway car trucks, particularly those of the cast steel integral journal box type, and has for its principal object the provision of a novel construction at the juncture of the compression and tension members with each other and with the journal box.

An important object of the invention is to provide a side frame in which the tension member is located above the upper inner edge of the journal box in spaced relation thereto, that is to say not directly connected therewith though braced with respect thereto by transverse force transmitting elements. 10
A more specific object of the invention is to provide a side frame in which the bottom wall or web of the tension member is in spaced relation to and above the upper inner edge of the box and in which ribs are provided 15 integral with the journal box and extending laterally from the sides of the tension member for transmitting to the latter the transverse forces or thrusts coming upon the journal box, these ribs obviating necessity for 20 providing a direct tie or other connection between the journal box and the bottom web or wall of the tension member.

A further object is to provide a construction of this character in which the bottom wall or web of the tension member is bifurcated from a point above the upper inner edge of the box to the end, the webs defined by the bifurcation gradually increasing in thickness toward the points where they merge 30 into the sides of the compression member to compensate for reduction in the area resulting from the bifurcation.

Yet another object is to provide a side frame in which a plurality of upstanding webs are provided rising from the roof of the journal box and merging into the inner faces of the sides of the juncture of the compression and tension members, these webs providing sufficient reinforcement that the 40 usual webs or ribs merging into the roof and the outer sides of the juncture may be omitted.

Furthermore it is an object to provide a construction of this character in which due 50 provision is made to insure strength and

rigidity without any chunkiness of the metal at any point or points.

An additional object is to provide a side frame possessing these meritorious characteristics and which will at the same time be 55 as simple and no more expensive to make than one of ordinary pattern, in addition to being efficient and durable in service, and a general improvement in the art.

To the attainment of the foregoing and other objects and advantages, the invention preferably consists in the details of construction and the arrangement and combination of parts to be hereinafter more fully described and claimed, and illustrated in the 60 accompanying drawing in which:

Figure 1 is a view of one-half of a side frame, the view being partly an elevation and partly a vertical longitudinal section,

Figure 2 is a fragmentary plan view, and 70

Figure 3 is a detail cross section taken on the line 3—3 of Figure 1.

Referring more particularly to the drawing which shows one-half of a side frame, this being sufficient as both sides are identically the same. This frame comprises compression and tension members 5 and 6, respectively, converging at their outer ends and united with an integral journal box 7. At their inner portions these members are 75 joined by column guides or pedestals 8 rising from the load supporting beam 9 which provides a seat 10 adapted to form a support for the usual or any preferred spring means for supporting the truck bolster, the bolster and springs being naturally located within the window opening 11 defined between the spaced column guides or pedestals 8. The juncture of the lower end of each column guide with the tension member 6 is preferably reinforced and the strain taken by inclined knees 12 and a somewhat similar structure 13 is provided at the juncture with the compression member 5. Any ordinary or preferred brake hanger bracket 14 is also provided in association with the column guides. These details are described for the sake of clearness and completeness of the disclosure but the invention lies in the construction at the journal box as will be described. 80 90 95 100

The compression and tension members 5 and 6 are channel shaped in cross section with their open sides extending toward each other, these open sides being formed with 5 stiffening beads 15 and 16, respectively. The outer end portion of the compression member 5 is rounded off at 17 from a point above the center of the journal box to the outer side thereof and the top wall of the compression 10 member is cut away or bifurcated at 18 from this same point to the end, thus defining webs 19 which gradually taper off or merge into the sides adjacent the end of the compression member. The confronting portions of the 15 compression and tension members are united at a point approximately above the inner edge of the journal box and the beads 15 and 16 join at this point designated at 20. Spaced inwardly from this point the 20 confronting sides of the compression and tension members are joined by downwardly and outwardly inclined ties 21 preferably stiffened by means of ribs 22 on their inner or confronting faces.

25 The bottom wall of the tension member 6 does not run directly into the journal box but is spaced therefrom and located an appreciable distance above the upper inner edge of the box as clearly shown in Figure 1.

30 For transmitting transverse forces from the box to the tension member, there is provided two external ribs 23 and 24 which extend diagonally upwardly and outwardly and which extend at right angles to the sides of 35 the tension member and also at right angles to the web thereof so that the lateral thrusts originating in the journal box will be communicated properly to the tension member. The web 23 disappears or merges into the 40 roof of the box near the forward edge or front thereof while the web 24 extends and merges into the dust guard wall 25 of the box. Though these webs are described as 45 extending at right angles to the web of the tension member they do not connect therewith as they connect only with the sides.

Beginning at a point above the inner upper edge of the box the web of the tension member is bifurcated or cut away as shown at 26, 50 thereby defining webs 27 which taper off and merge into the metal at the sides of the juncture of the compression and tension members. To compensate for the loss of area resulting from this bifurcation the webs 27 55 gradually increase the thickness as they approach and merge at 28 into the metal at the juncture referred to, this point being moreover above the center of the journal box.

To stiffen the journal box roof so that it 60 will have sufficient strength and rigidity to oppose thrusts thereon, there is provided a plurality of substantially triangular ribs or webs merging into the roof of the box and into the inner sides of the metal at the juncture of the compression and tension mem-

bers. These pairs of ribs are designated at 29 and 30 and it will be observed that the former are located beneath the webs 27 while the latter are located outwardly of the points 70 28. These pairs of ribs are located also at 75 opposite sides of the longitudinal center of the box and are preferably equi-distant from said center. By virtue of the provision of these pairs of ribs it will be unnecessary to provide the usual external ribs, that is to 80 say ribs rising from the roof of the box and joined onto the outer sides of the juncture.

The neutral axis of each column guide is indicated by the line 31 and intersects the neutral axes 32 and 33 of the compression and 85 tension members at the points 34 and 35, and the neutral axes 32 and 33 intersect at a point 36 above the center of the journal box, in fact immediately adjacent the point 28.

From the foregoing description and a 85 study of the drawing it will be seen that there is thus provided a side frame which is used in exactly the same manner as any other but which is a distinct departure from ordinarily accepted designs in that while the 90 sides of the tension and compression members merge into each other and into the journal box the web of the tension member is definitely spaced therefrom. Ample provision is made, by virtue of the existence of the webs or ribs 23 and 24, for properly transmitting lateral forces from the box to the tension member so that there will be unusual strength at this point. The box roof is well braced so as not to be subject to buckling or other 95 distortion and in fact every contingency has been contemplated and provided for. It is believed from the above that the construction and advantages will be readily apparent to one skilled in the art without further explanation.

While there has been shown and described the preferred embodiment of the invention, it should be understood that the disclosure is merely an exemplification of the principles involved as the right is reserved to make all such changes in the details of construction as will widen the field of utility and increase the adaptability of the device provided such changes constitute no departure from the 100 spirit of the invention or the scope of the claims hereunto appended.

Having thus described the invention, the following is claimed:

1. In a side frame, compression and tension members converging at their outer ends and merging into each other and into an integral journal box, the tension member being of channel shape in cross section with its open side uppermost, the web or bottom wall of the tension member extending above the upper inner edge of the journal box and being free therefrom.
2. In a side frame, compression and tension members converging at their outer ends 120 125 130

and merging into each other and into an integral journal box, the tension member being of channel shape in cross section with its open side uppermost, the web or bottom wall of the tension member extending above the upper inner edge of the journal box and being in spaced relation thereto.

3. In a side frame, compression and tension members converging at their outer ends and merging into each other and into an integral journal box, the tension member being of channel shape in cross section with its open side uppermost, the web or bottom wall of the tension member extending above the upper inner edge of the journal box and being in spaced relation thereto, and means connecting the sides of the tension member with the journal box for transmitting lateral forces from the latter to the former.

10 4. In a side frame, compression and tension members converging at their outer ends and merging into each other and into an integral journal box, the tension member being of channel shape in cross section with its open side uppermost, the web or bottom wall of the tension member extending above the upper inner edge of the journal box and being in spaced relation thereto, and ribs joined to the upper inner edge portion of the journal box and merging into the sides of the tension member.

5. In a side frame, compression and tension members converging at their outer ends and merging into each other and into an integral journal box, the tension member being of channel shape in cross section with its open side uppermost, the web or bottom wall of the tension member extending above the upper inner edge of the journal box and being in spaced relation thereto, and diagonal ribs extending upwardly from the upper inner edge portion of the journal box and merging into the sides of the tension member in right angular relation thereto.

40 6. In a side frame, compression and tension members converging at their outer ends and merging into each other and into an integral journal box, the tension member being of channel shape in cross section with its open side uppermost, the web or bottom wall of the tension member extending above the upper inner edge of the journal box and being in spaced relation thereto, and diagonal ribs extending upwardly from the upper inner edge portion of the journal box and merging into the sides of the tension member in right angular relation thereto, one of said ribs disappearing adjacent the front of the box and the other extending to the dust 45 guard wall thereof.

7. In a side frame, compression and tension members converging at their outer ends and having their sides merging into each other and into an integral journal box, said tension member having a bottom web

extending above the upper inner edge of the box in spaced relation thereto, and ribs formed at the upper inner edge portion of the box and inclining upwardly toward the center of the frame and joined to the sides of the tension member in right angular relation thereto.

In testimony whereof we affix our signatures.
